GROUND GRIPPING MEANS FOR GUN MOUNTS

Jacques Marcel Jules Riboud, Mount Washington, Md., assignor to Specialty Equipment and Machinery Corp., New York, N. Y., a corporation of Maryland

Application December 22, 1941, Serial No. 423,893

5 Claims.

(Cl. 89—40)

The present invention relates generally to armored enclosures.

An important factor in all gun mounts is the matter of recoil absorption. In all cases, adequate provision must be made for the recoil, if the gun is to be used efficiently. Field guns which have a single tailstock have a horizontal arc of coverage which is severely limited to approximately 15° of the horizon. The arc of coverage is greater with field pieces having a double tailstock, but if it is sought to increase the degree of coverage, the sweep of field, tailstock guns have proven to be unsatisfactory because the recoil tends very quickly to shift the gun and its mount out of line. In an earlier application, Serial No. 417,260, now Patent 2,361,570, dated October 31, 1944, I disclosed an armored enclosure having a completely revolvable turret so that the gun therein has full 360 degrees of horizontal coverage. In the present application, the main object is the provision of means to so support an armored enclosure and secure same to the ground as to fully absorb the recoil and prevent the gun mount from shifting from its set position irrespective of the direction of gun fire. Put in another way, the main object of my invention is the provision of a ground support which will absorb the horizontal component of the forces generated by the recoil of the gun regardless of its direction of fire.

Another object of my invention is the provision of a support which may be removably fixed into the ground by the combined weight of the gun, the weight of the thrusting medium, and the thrusting force.

A further object of my invention is the provision of armored enclosure supports which may be swung up out of the way when the enclosure is being moved from one site to another; which may be used to help support the enclosure during travelling movement, and which may be shifted into position for use quickly, simply and without any difficulty.

A further object of my invention is the provision of ground support means for an armored enclosure which comprise a plurality of individual leg members, adjustable as to length, having ground gripping means at the ends thereof.

A further object of my invention is the provision of means to support an armored enclosure with respect to the ground, which means are individually adjustable as to height, and which are provided with ground gripping means.

A further object of my invention is the provision of means to support an armored enclosure

with respect to the ground, which means comprise a plurality of individual leg members, pivotally secured to the enclosure so as to be swingable thereunder out of the way during travelling movement, and dropped down when it is desired to "set" the enclosure, the said legs being individually adjustable in height and having ground gripping means at the free ends thereof.

In the drawings annexed hereto forming a part hereof,

Figure 1 is a side elevational view of one form of device constructed according to and embodying my invention during travelling movement with the supporting legs swung up out of the way;

Fig. 2 is a similar view of this modification showing the legs dropped down preparatory to fixing the device into the ground;

Fig. 3 is a similar view of this modification showing the legs in fixed position on the ground;

Fig. 4 is an enlarged side elevational view of the leg and one form of ground gripping component which I may use to fix the leg into the ground;

Fig. 5 is an end elevational view thereof partly in section;

Fig. 6 is a perspective view of the blocks or chocks I employ in this form of ground gripping mechanism;

Fig. 7 is a top plan of the ground gripping plate;

Fig. 8 is a side elevational view of a modified form of enclosure support constructed according to my invention; and

Figs. 9 and 10 are similar elevational views showing successive stages in the erection of the mounting and ground gripping mechanisms.

In the modification of Figs. 1 to 3, the armored enclosure is referred to generally by reference numeral 10, comprising a rotatable turret mounted on a generally rectangular frame 11 supported on its rear end by a pair of wide spaced wheels 12, 12 and at its front end by a pair of legs 14, 14. Legs 14, 14 are preferably of telescope construction, that is, they may be lengthened or shortened, as desired, to compensate for local ground conditions. As shown in Fig. 1, legs 14, 14 are pivotally mounted as at 16, at the front end of frame 11, so that they may be swung up underneath the frame. The axis of the mounting is parallel to the front of the frame, and when the legs are swung up underneath the enclosure frame during travel, the legs extend toward the rear of the device in parallelism with the length of the frame.

The yoked bottom end 18 of each leg 14 has a

wheel 20 secured thereonto. Wheel 20 has formed thereon a plurality of annular corrugations 22, 22, extending substantially across the full width of the wheel face. While the front legs 14, 14 and wheels 20, 20, may help to support the unit during travelling, the main purpose in their provision is to act in absorbing the gun recoil. Preferably, during travelling movement, the legs 14, 14 are swung up alongside or underneath frame 11, out of the way, and support for the unit is distributed between the rear wheels 12, 12, and the conveying vehicle indicated by reference numeral 25 which is attached to shaft 15.

I provide a generally rectangular ground gripping plate 30, preferably of flat heavy metallic construction, which has a number of large, pointed spikes 32 on the underside thereof. On the upper surface of the plate I form a plurality of corrugations 34 of height and width equal to the annular corrugations 22 about wheels 20. Plate 30 is appreciably longer and wider than wheels 20, 20, and to prevent any relative lateral movement of the wheels and plates, I provide for each wheel and plate combination a pair of blocks or chocks 40, 40. These blocks 40 are roughly triangular in cross section, and the base 44 of each block is transversely corrugated, as at 46. The inner side 48 of each block is corrugated, as at 50. Each block is laterally apertured as at 52, and a number of bails or straps 54, 54 are provided which may be removably secured to the blocks so that they can be assembled with the wheels and plates easily and quickly.

On the corrugated upper side of plate 30, I secure two pairs of apertured upstanding flanges 60, 60 on opposite sides of and adjacent to the corrugations 34. I also provide elongated slide pins 62, 62 adapted to fit through the apertured flanges.

In assembling the ground gripping components of this modification of my invention, bails 54 are threaded over wheel 20, the ends being anchored in the blocks 40, 40, to secure the blocks to the wheel. The corrugations 22 on the wheels interfit snugly with the corrugations 50, 50 on the inner sides 48, 48 of the blocks and the bails are formed of such length as to insure a close grip between the wheel and block assembly which is then mounted onto plate 30. The corrugated undersides 46 of the blocks and the wheel corrugations 22 fit onto the plate corrugations 34. Pins 62 are then passed through the registering flange apertures 60 and block apertures 52, to lock the block and wheel assembly onto the plate. Suitable means are provided to keep the slide pins locked in place through the flanges and the blocks.

When the enclosure is moved into position for firing, legs 14 with the wheel and block assembly secured thereonto, are dropped down until the plate spikes 32 touch the ground, as shown in Fig. 2. The propelling vehicle 25 is then backed up, pushing against the legs. While such movement has a normal tendency to raise the front shaft end 15 of the enclosure and also the rear end of the propeller 25, the rearward moving force of the propeller mechanism, acting upon the ground engaged plates, is multiplied by the combined factors of the weight of the enclosure and the weight of the propeller, and the plates 30, 30 are driven into the ground under this force until the body thereof is flush with the ground. I also provide means to lock the legs 14, 14 as they are brought into position at right angles to the frame under the thrust of the propeller mechanism.

The corrugated interfit between the wheels, blocks and plate insure against any side-skid of the wheels with respect to the plates. Normally, the strength of the engagement between the wheels and plate exceeds that of the recoil of the firing mechanism, so that any sidewise or endwise movement of the gun legs will be prevented no matter from what angle the gun is fired. When it is desired to shift the unit, the moving vehicle is attached to shaft 15 and the leg locks are released. Traction is applied in a forward direction and as the frame is carried forwardly, the legs 14 are pulled up and out of the ground, whence they may be swung up out of the way against the underside of the frame.

The corrugations are provided on the wheel, block and plate assembly so that when the wheels at the ends of the legs are submitted to the thrust created by the recoil of the gun when the gun is fired at an angle with respect to the platform, they will be prevented from and held against skidding along their rotational axis off the plate. The important feature of my invention is the pivotally mounted legs, adjustable as to length, having ground gripping means at the ends thereof, and the block and wheel arrangement, while novel, is secondary in importance to the main concept of my invention.

In Figs. 1 to 7, I have shown one form of leg and ground gripping mechanism wherein the wheels and blocks are employed, but in Figs. 8 to 10, I have illustrated another form of leg arrangement, doing away with the wheels and blocks.

In the form of Figs. 8 to 10, legs 70, 72 are each individually adjustable as to length, and at the bottom ends thereof, I pivotally mount a plate 80 thereto, so as to swing or rock back and forth along an axis parallel to the axis of the leg connection to frame 11. In this form, I eliminate the wheel and the blocks and mount the ground gripping plate 80 directly onto the end of the leg, and while I have shown a straight line rocking action between plate 80 and legs 70, 72, I may equally well provide a universal pivot connection therebetween.

In Figs. 8 to 10, the armored gun carrying enclosure 100, is mounted on frame 102, having a shaft 104 extending forwardly thereof. This shaft 104 is connected to the moving vehicle, as 25 (see Figs. 1 to 3), when it is desired to transport the enclosure from one site to another. A pair of wheels, as 106, are provided at each end of frame 102, to support frame 102 above ground G during travelling movement. A pair of legs 70, 72 are provided at each end of frame 102. Front legs 72, 72 are shown to be telescoping, that is, they may be adjusted as to length, and while rear legs 70, 70 are shown to be of fixed length, they may within my invention be of telescopic construction also.

Legs 70, 72 are pivotally mounted on frame 102, as at 108, and may be swung up alongside the frame, out of the way, during movement of the gun. The axis of the leg mountings are parallel and all the legs are swingable rearwardly, parallel to the frame. The ends of legs 70, 72 are yoked, or bifurcated as at 75 so as to receive plates 80 thereon. These plates 80, similar to plates 30, are flat, heavy metallic members, rectangular in shape, having a plurality of long, sharp projections 82 projecting downwardly therefrom. Plates 80 are pivotally mounted onto the legs as by pins 77, so that when the legs are in the "up" position of Fig. 8, the projections 82

will extend downwardly towards the ground G, and when the legs are dropped (as in Figs. 9 and 10) the plates 80 will parallel the ground. Legs 70, 72 are preferably longer than the distance between the frame 102 and the ground when the frame is supported on the wheels 106, and when legs 70, 72 are initially dropped to the ground, they will be angled as shown in Fig. 9.

As traction or pushing pressure is applied, the projections 82, 82 will be forced into the ground under the combined force of the moving vehicle, the weight of the enclosure and the weight of the moving vehicle. As the frame and enclosure are moved forwardly, they are shifted from the support of wheels 106, 106 onto the support of the ground gripping legs 70, 72, and the frame and wheels lifted above ground level. As the frame is moved forwardly, the legs 70, 72 are pivoted about pins 77 into right angle relation to frame 102, and they may be locked in that position against the frame as by clamp 90 fitting over headed extensions 92 on the sides of the legs. Similar means are provided to lock legs 14, 14 onto frame 11, in the modification of Figs. 1 to 3.

In both modifications, the desideratum is the same, that is, individually mounted legs, adjustable as to length, having ground gripping means thereon. In the first form, I have illustrated and described a special type of ground gripping plates and means to secure same to the wheeled legs. In the second form of my invention, the plates are permanently connected to the jack legs. The jack legs of Figs. 8 to 10 and those of Figs. 1 to 3 may be interchangeably employed, since both operate in the identical manner to support the enclosure during gun firing to prevent any side-wise or endwise movement. The particular types of supports for travelling movement which I have shown in both forms are illustrative, and do not limit my invention. Obviously, the ground gripper adjustable legs of my invention may be employed with other types of supports and in my invention is to be limited only by the scope of the annexed claims.

I claim:

1. A platform, a gun thereon, and means to support the platform in spaced relation to the ground and means to prevent side- or end-wise shifting of the platform during firing of the gun, the supporting means comprising a pair of legs at one end of the platform, each leg having a wheel at the terminal end thereof, the shift preventing means comprising a flat, ground contacting plate and a pair of blocks for each wheel secured between the wheel and the plate.

2. A platform, a gun thereon, and means to support the platform in spaced relation to the

ground and means to prevent side- or end-wise shifting of the platform during firing of the gun, the supporting means comprising a pair of legs at one end thereof, each having a wheel at the bottom thereof, each wheel having a plurality of annular corrugations about the periphery thereof, the shift preventing means comprising a plate for each leg, corrugations on the upper side of each plate, the wheel and plate corrugations interfitting and means to secure the wheels to the plates.

3. A platform, a gun thereon, and means to support the platform in spaced relation to the ground and means to prevent side- or end-wise shifting of the platform during firing of the gun, the supporting means comprising a pair of legs at an end thereof, each leg having a wheel thereon, and each wheel having a plurality of annular corrugations, and means to prevent shifting of the platform comprising a ground gripping plate for each wheel, the upper surface being provided with a plurality of corrugations into which the wheel corrugations interfit, a pair of blocks for each wheel, means to secure same to the wheel and means to secure the blocks to the plate.

4. A field piece comprising a platform, a gun containing turret thereon revolvable about 360° of horizon, means to support the platform in spaced relation to the ground comprising a pair of wheels permanently secured at one end of the platform, and a pair of jack legs at the opposite end, said jack legs during movement of the piece from one site to another being swingable up against the platform out of contact with the ground, and means to prevent shifting of the platform during firing of the gun, the shift preventing means comprising the jack legs each of which has a substantially flat ground gripping plate secured to the bottom of each leg and pivotally mounted thereon.

5. A field piece comprising a generally rectangular, flat platform, a gun containing turret thereon revolvable about 360° of horizon, and means to support the platform in spaced relation to the ground, said supporting means comprising a pair of wheels at one end of the platform and a pair of individually adjustable jack legs at the other end of the platform, and means to prevent side-wise or end-wise shifting of the platform during firing of the gun comprising a pair of substantially flat plates, means to pivotally secure one of the plates to the bottom of each leg and cooperating means on the legs and plates to prevent side-wise or end-wise shifting of the legs relative to the plates secured thereto.

JACQUES MARCEL JULES RIBOUD.
